UNITED STATES PATENT OFFICE.

ALBION PARRIS MERRILL AND JENNY WARD HAYS, OF SAN FRANCISCO,
CALIFORNIA.

TELEPHONE.

SPECIFICATION forming part of Letters Patent No. 669,944, dated March 12, 1901.

Application filed January 10, 1900. Serial No. 1,008. (No model.)

To all whom it may concern:

Be it known that we, ALBION PARRIS MERRILL and JENNY WARD HAYS, citizens of the United States, and residents of the city and county of San Francisco, in the State of California, have invented a new and useful Telephone, of which the following is a specification.

This invention relates to improvements in telephones.

10 Telephones as commonly employed do not transmit sound as originally produced, but reproduce it in decreased volume and strength, necessitating the closest attention at the receiver and with the instrument held to the 15 ear in order to distinguish and understand the sounds or message transmitted.

It is one object of the present invention to construct a telephone to overcome this objection and render possible the reproduction or 20 transmission of sound with nearly or quite its original volume and strength, so that the same will be audible and distinguishable in any part of a room or chamber in which the receiving instrument is located and without the 25 necessity of holding an instrument to the ear.

A further object is the production of a telephone in the use of which it is not necessary for the party sending a message to approach the transmitter and talk directly into the 30 same, as is required in the use of the common types of telephones, but which transmitter will properly transmit speech or sounds produced in the room in which the transmitter is located and at a distance from the instrument.

35 These objects we accomplish primarily by the employment of a novel construction of mouthpiece for the transmitter and receiver of novel construction and by novel parts, arrangements, and combinations of parts hereinafter described.

A further object is to provide means to soften the sounds entering the transmitter.

40 A further object is to provide means for 45 limiting the circular vibrations of the receiver-diaphragm to articulate sounds having the effect of cutting the words and syllables off short and clear, to soften the speech, relieve it of metallic sound, and make it more 50 natural.

A further object is to provide a novel sys-

tem of wires and switches whereby a transmitter can be cut out while the telephone is being used, so that while sounds will be transmitted to and received by one instrument they 55 will not be transmitted from said instrument.

A further object is to prevent the formation of a dead-air cushion against a receiver-diaphragm, which, if permitted, would prevent the successful operation of the receiver 60 for the intended purpose.

With such and other objects in view the invention is embodied in the novel parts, arrangement, and combination of parts herein-after described, and particularly set forth in 65 the claims.

In the accompanying drawings we have illustrated an embodiment of our invention, but desire it understood that we do not limit the invention in its useful applications to the 70 construction which is there shown simply to give a better understanding of the invention.

In said drawings, Figure 1 is a perspective view of the instrument without the electrical connections. Fig. 2 is a longitudinal sectional view of the transmitter. Fig. 3 is a similar view of the receiver, showing a portion of the box of the instrument and part of the receiver-magnet. Fig. 4 is a perspective view showing two instruments with their 80 electrical connections. Fig. 5 is a diagrammatic view showing the application of the telephone for use in theaters, public halls, or the like. Fig. 6 is a perspective view of a mute intended to be used with the receiver 85 when it is desired to diminish the volume of the sound so that it may only be heard by the intended person.

Referring to said drawings, wherein like reference characters refer to similar parts 90 throughout the several views, A indicates a box which constitutes the support and inclosure for the several parts of the instrument. The receiver, which is indicated at C, is fixed to a part of this box, and in order to prevent 95 the formation of a dead-air cushion against the diaphragm of the receiver the box is provided with a hole or holes A². In this respect the invention differs from the ordinary telephone in general use in which the receiver is not a fixture of the box and in which the box is closed. To close the box entirely 100

deadens or muffles the vibration of the diaphragm, whereas the open framework or perforated box, as shown, insures a louder and clearer reproduction of the sound by the receiver. If desired, suitable screens or reticulated material A³ may be provided to cover the openings to prevent the entrance of dust or foreign matter into the box.

B indicates a transmitter, which is shown as secured to an extension A⁴ of the rear portion of the box. The transmitter extends forwardly from this extension A⁴ over the body of the box A. The transmitter proper may be of any suitable or preferred construction, it forming no part of the present invention, and we have illustrated in the drawings what is known as the "long-distance" transmitter. It comprises, briefly stated, a sheet-metal box or shell B², holding a cup B³, of carbon or other suitable substance, through which is passed a screw B⁴, to which one of the wires of the local or primary circuit is attached. An annular groove is formed in the cup B³, in which groove is placed a ring B⁵, conveniently made of plush, cotton, or felt, and within this ring B⁵ is located a circular piece of soft rubber B⁶, provided with circular concentric corrugations or grooves B⁷, adapted to hold the carbon granules indicated at B⁸.

B⁹ indicates the transmitter-diaphragm, which is placed over the granules. Connected to the shell B² by means of a binding-screw B¹⁰ is the other wire of the local or direct circuit.

We make no claim to the portions of the transmitter thus far described, our invention in the transmitter relating to a novel mouthpiece (shown at B¹¹) and an outer large front diaphragm B¹², secured over the mouth or large end of the mouthpiece. The mouthpiece is secured in any preferred manner to the transmitter proper, and its inner or operative surface is parabolic in contour. The object of providing the mouthpiece with the inner parabolic surface is to focus the sounds received by the mouthpiece to a given point at the center of the transmitter-diaphragm B⁹, as indicated by the dotted lines in Fig. 2, thereby concentrating the sounds and increasing the efficiency of the transmitter. The diaphragm B¹² is conveniently made of bladder, paper, parchment, isinglass, or other suitable light material and is adapted and acts to soften the sounds when the same are too harsh—as, for instance, when produced by brass instruments. The diaphragm B¹² creates an air-cushion in the mouthpiece between itself and the transmitter-diaphragm which acts on the transmitter-diaphragm. While the diaphragm B¹² provides better results, we do not wish to limit our invention necessarily to the employment of the same, as the receiver will operate in a highly satisfactory manner without said diaphragm.

Referring to the receiver, which is shown in detail in Fig. 3, C indicates a mouthpiece

or trumpet comprising two portions, the outer or larger portion having, like the mouth of the transmitter, an inner parabolic surface 70 and the inner or base portion C² having a hyperbolic inner surface, which is preferably provided with a lining C³, of felt or similar material, which is smoothly secured thereto and has substantially the same contour as the 75 inner surface of the portion C² of the mouthpiece. The portion C² of the mouthpiece is provided with a base-securing flange C⁴, by means of which it is secured directly to the box A or a door A⁵ of the box. Interposed 80 between this flange and the box or the door is an annular washer or pad C⁵, its purpose being to prevent the resonance of the wood or other material of which the box is formed.

C⁶ indicates the diaphragm of the receiver, 85 which, it will be observed, is of comparatively large area and is secured at its outer circumferential edge to the flange C⁴, an annular pad or washer C⁷ being interposed between the diaphragm and said flange, which pad prevents 90 the metallic sound or ring of the base of the mouthpiece being transmitted to the receiver-diaphragm.

C⁸ indicates an annular pad, which lies flat against the inner surface of the diaphragm 95 C⁶ and extends over a large part thereof.

The several pads C⁵, C⁷, and C⁸, together with the diaphragm and flange C⁴, are secured to the box or box-door in any preferred manner—as, for instance, by means of the metallic 100 ring C⁹, placed on the pad C⁸ and secured to the box, as by screws, (indicated at C¹⁰.)

It will be noticed from the construction of the receiver-mouthpiece, as indicated by the dotted lines in Fig. 3, that the sounds produced by the diaphragm C⁶ if not going out directly through the receiver are directed onto the parabolic surface of the outward portion from any point at which they strike the hyperbolic base portion and that they are reflected from the parabolic mouth of the receiver in straight lines. This novel formation of the receiver-mouthpiece affords a deep air-chamber between the diaphragm and the hyperbolic surface of the portion C², and these, 115 in combination with the parabolic outlet, assist materially in the transmission of the sounds, which are delivered in full volume.

The purpose of the pad C⁸, which lies flat against the receiver-diaphragm, is to limit the circular vibration of the diaphragm to articulate the sound and has the effect of cutting the words and syllables off short and clear. The purpose of the felt lining C³ in the parabolic portion of the mouthpiece is to soften 125 the speech, take away the resonance of the metal, and make the resultant sound more natural. These are vital points to successful articulation. It will be observed that the hyperbolic base portion of the mouthpiece receives the sounds delivered from any part of the relatively large diaphragm and reflects the same into the parabolic portion of the mouthpiece and that the parabolic outer por-

tion sends the sounds out in straight lines. Located back of the receiver-diaphragm C⁶ is an electromagnet of the receiver, (indicated at C¹¹,) which is shown as having spools C¹², which are flattened and are placed on flattened cores, the purpose being to obtain a magnet of large working area and at the same time one having its force concentrated on the center of the diaphragm. The magnet is supported conveniently by a bracket, such as C¹³, secured to the box A or box-door A⁵.

D indicates an induction-coil, which is shown as located in the instrument-box and having, as usual, a primary and secondary winding.

E indicates a battery for the local circuit located also in the box of the instrument.

One battery is provided for each instrument, being connected up in the local circuit thereof.

For an understanding of the electrical connections attention is directed particularly to Fig. 4, which illustrates two instruments, each comprising a receiver, transmitter, induction-coil, and local-circuit battery, the two instruments being electrically connected. It will be observed that the primary coil of the induction-coil in each instrument is in and operated by the direct current from the battery of the instrument E. The receiver in each instrument, on the other hand, is operated by and located in the secondary or induced current circuit. The current for each transmitter flows, say, from the point marked + at the battery E in the upper instrument, (indicated in Fig. 4,) thence along the primary-circuit wire F to the primary coil of the induction-coil D, along the wire G to the transmitter B, through the transmitter along the wire H to the switch J, and thence back to the battery at the place indicated by the - sign by the wire K. The primary circuit of the lower or other instrument shown in Fig. 4 follows an exactly similar course and, like the primary circuit of the upper instrument, is provided with a switch. These switches when open not only save the current from the batteries when the instruments are not in use, but also permit of one transmitter being cut out when the instruments are being used, so that sounds can be received by either instrument, but will not be transmitted from the instrument at which the switch is opened.

The receiver-circuit for the receiver of the upper instrument (shown in Fig. 4) is connected with the transmitter of the lower instrument and begins, say, with the secondary winding of the induction-coil D of said lower instrument and follows the course indicated by the arrows X along the wire a to the post No. 1 of the lower instrument, along the wire b to post No. 2 of the upper instrument, thence along wire c, plate d, flexible connection e, which latter is interposed for the purpose of permitting the swing of the door, to post f, thence along wire g to the electro-

magnet C¹¹ of the receiver of the upper instrument, thence along wire h to post i, flexible connection j to post No. 3 of the upper instrument, thence along wire m to post No. 3 of the lower instrument and wire m², which latter is practically a continuation of the wire m, and finally back to the secondary winding of the induction-coil D of the lower instrument, thus completing the receiver-circuit for the upper instrument. The circuit for the receiver of the lower instrument follows a like course, as will be seen from Fig. 4. It begins, say, with the secondary winding of the upper coil D, following the course indicated by the arrows y, along the wire a to post No. 1 of the upper instrument, the wire b to post No. 2 of the lower instrument, wire c, plate d, and flexible connection e to the electromagnet of the receiver of the lower instrument, which latter is not shown, thence to the flexible connection j, to post No. 3 of the lower instrument, along the wire m in the direction indicated by the arrow y to the post No. 3 of the upper instrument, wire m², which latter, like wire m² in the lower instrument, is, in effect, a continuation of the wire m, and back to the secondary winding of the induction-coil D of the upper instrument, thus completing the circuit.

It is to be noted that the circuit for both receivers is completed through a single wire m with its continuations m² m². In other words, this wire m is common to both receiver-circuits and is, in effect, a third wire or single return-wire for both circuits.

M, Fig. 6, indicates a mute or attachment which may be used in connection with the receiver above described when desired. This mute comprises a parabolic trumpet or portion M², provided with a suitable handle M³, which trumpet M² is adapted to be placed over the funnel-mouth or large end of the receiver, as indicated by dotted lines in Fig. 1. It also comprises a flexible tube M⁴ and ear-piece M⁵ at the end of said flexible tube. The object of the mute is to concentrate, deaden, or diminish the volume of the sound from the receiver, so that it may be heard only by the person using the instrument and who holds the earpiece M⁵ to the ear.

In Fig. 5 of the drawings we have shown diagrammatically one application of our improvement, wherein an instrument having a transmitter is shown as located at a convenient point on the stage of a theater, hall, or the like, said instrument (indicated at O) being properly connected to other instruments O² O³ O⁴ O⁵, provided with our novel receivers and located at various points about the body of the hall or theater. With this arrangement the speech or song or other sounds desired to be heard which are produced on the stage are received by the several instruments about the auditorium and are delivered in full volume at the various points where the instruments are located,

thus enabling the audience in the remote parts of the auditorium to hear distinctly and understand the sounds produced on the stage.

Many other applications of the telephone will readily suggest themselves.

We do not deem it necessary here to go into a lengthy discussion of the numerous and various applications of the apparatus.

It is believed that from the above description and the drawings the operation of the telephone will be readily understood.

Having thus described the invention, what we claim as new, and desire to secure by Letters Patent, is—

15 1. In a telephone, a receiver, and a fixed box or frame on which the same is mounted and in which the operating parts of the receiver and battery are located, said box or frame having an opening or openings to prevent a dead-air cushion therein, substantially as described.

20 2. In a telephone, a transmitter provided with a mouthpiece having an inner parabolic surface increasing in diameter from the inner small end to the outer large end, and so positioned relative to the transmitter-diaphragm as to focus the sounds received by the mouthpiece at the center of the diaphragm, substantially as described.

25 3. In a telephone, a transmitter provided with a mouthpiece having an inner parabolic surface increasing in diameter from the inner small end to the outer large end, and so positioned relative to the transmitter-diaphragm as to focus the sounds received by the mouthpiece at the center of the diaphragm, and a diaphragm closing the large or outer end of the mouthpiece, substantially as described.

30 4. In a telephone, a receiver comprising a

diaphragm and a mouthpiece or trumpet for 40 said diaphragm provided with an inner hyperbolic portion, and outer parabolic portion, substantially as and for the purpose specified.

5. In a receiver for telephones, the combination of a support, a receiver-mouthpiece 45 secured to said support and having interposed between it and said support a cushion or pad, a pad or cushion C⁷ on said mouthpiece, a receiver-diaphragm on said pad C⁷, a pad C⁸ extending over a large area of the diaphragm 50 on the side opposite said pad C⁷, and means for securing the several pads and diaphragm to said support, substantially as described.

6. In a telephone, a receiver comprising a diaphragm, and a mouthpiece or trumpet 55 therefor provided with an inner hyperbolic portion, and an outer parabolic portion said inner portion having a soft lining, substantially as described.

7. In a telephone, a box, or frame, a receiver 60 fixed thereon, the operative parts of which receiver are located in the box or frame, a transmitter fixed on said box, an induction-coil for the transmitter located within said box, a battery located in said box or frame, said box 55 or frame having an opening or openings to prevent a dead-air cushion therein, and suitable electrical connections, substantially as described.

In testimony whereof we have signed our 70 names to this specification in the presence of two subscribing witnesses.
